UNITED STATES PATENT OFFICE.

ALBERT REYNOLDS, OF SAN JOSE, CALIFORNIA.

PACKAGING-MACHINE.

1,359,429.

Specification of Letters Patent. Patented Nov. 16, 1920.

Application filed March 4, 1920. Serial No. 363,245

To all whom it may concern:

Be it known that I, ALBERT REYNOLDS, a subject of the King of Great Britain, and resident of San Jose, in the county of Santa Clara and State of California, have invented certain new and useful Improvements in Packaging-Machines, of which the following is a specification.

My invention relates to machines for forming paper packages, filling the same with a given quantity of material and discharging the same. The object of my invention is to provide a machine of the character indicated that will automatically and continuously form a succession of paper packages, place and compress the given quantity of material in each package, close the package and discharge the same. Other objects are to provide a machine of the character indicated that will be compact in form, simple and accurate in operation and highly efficient in its practical application.

In the drawing:—

Figure 1 is a front elevation of my improved machine.

Fig. 2 is a side elevation of my improved machine.

Fig. 3 is a sectional view on 3—3 of Fig. 2.

Fig. 4 is a sectional view on 4—4 of Fig. 2.

Fig. 5 is a section on 5—5 of Fig. 2.

Fig. 6 is a detail plan view of the paper seaming device.

Fig. 7 is a sectional view on 7—7 of Fig. 2.

Fig. 8 is a section on 8—8 of Fig. 7.

Fig. 9 is a sectional view on line 9—9 of Fig. 2.

Fig. 10 is a detail sectional view of the cam member alone on line 8—8 of Fig. 7.

Fig. 11 is a detail plan view of the package removing device on line 11—11 of Fig. 2.

Fig. 12 is a perspective view of the folded and seamed paper tube perforated in accordance with my invention, part broken away.

Fig. 13 is a perspective view of the portion of the paper tube shown in Fig. 12 with portions of the sides separated and folded inwardly to form parts of the ends of two packages.

Fig. 14 is a perspective view of the portion of the tube shown in Fig. 12 with portions of the sides and edges separated and folded inwardly to form completed ends for two packages.

Fig. 15 is a perspective view of one of the rollers used in perforating and folding one

of the edge end portions of the paper tube as shown in Fig. 14.

Fig. 16 is a perspective view of one of the rollers used in perforating and rolling one of the side end portions of the paper tube as shown in Fig. 14.

Fig. 17 is a section on line 17—17 of Fig. 1.

Figs. 18 to 22 inclusive are diagrammatical illustrations of the successive positions of the package handling plungers.

Figs. 23 to 31 inclusive are cam graphs.

The operation of the machine herein described is divided into three major movements, viz., the placing and packing of the material; the forming of the paper envelop around each charge of material formed and packed; the removal of the wrapped charge to a position for placing in a carton. These movements are, however, interdependent and coöperate to secure the desired results as herein described.

Referring more particularly to the drawings, 1 indicates a suitable hollow standard carrying a revolving cam member 2 and a table 3 supporting a frame 4 which in turn supports and positions the mold 5 and parts connected thereto.

The placing of the material is effected as follows. The mold 5 communicates with supply chamber 6 through opening 7, the chamber 6 receiving a given quantity of material at stated periods. At 8 is shown a plunger fitting closely in the bottom and sides of chamber 6 and operated by rod 9 extending through bearing 10 and provided with a terminal pin 11. At 12 is shown a bell crank pivoted at 13 upon a bracket 14 rigidly mounted upon the machine, the outer arm thereof having a slot 15 formed therein to slidably engage pin 11. The inner arm of bell crank 12 extends through slots 16 in supply chamber 6 and into molds 5 and is forked as at 17 to engage the opposite sides of rack 18 operating in said mold, the said rack having vertical slots formed therein as at 19 for receiving forked arm portions 17 as shown. A head 20 is shown upon the lower end of rack 18 properly proportioned to slide freely in mold 5. These parts coöperate in such a manner that when the head 20 moves downwardly the upper ends of slots 19 engage portions 17 thereby operating bell crank 12 to withdraw plunger 8 to the position shown in Fig. 17. As the

105

110

said head 20 approaches the end of its upward stroke the lower ends of slots 19 engage the portions 17 thereby operating bell crank 12 to move plunger 8 to the position 5 shown in dotted lines in Fig. 17, whereby material dropped into chamber 6 is moved forward and caused to fall into mold 5 where it is forced down by the next downward movement of head 20.

10 The head 20 is reciprocated through the medium of a rack 18 in the following manner. At 21 is a pinion engaging rack 18 and mounted on shaft 22 revolving in bearings 23 and carrying a second pinion 24. 15 At 25 is a sector gear revolvably mounted at 26 and in permanent engagement with pinion 24. Sector 25 is provided with a pinion 27 which is in permanent engagement with a pinion 28 revolvably mounted at 29 20 and carrying an arm 30. At 31 is a link connecting arm 30 with another arm 32, the latter being pivoted at 33 on a bracket 34 mounted on frame 4 and carrying a sector gear 35 engaging a rack 36 mounted to reciprocate vertically as shown. Rack 36 is 25 offset at its lower end and provided with a roller 37 adapted to engage the upper edge of cam member 2 and also the groove 38 formed in extension 39 thereon. The edge 30 of cam member 2 opposite to groove 38 is formed as shown at 40 so that when the said cam member is revolved in the direction indicated by the arrow the cam surface 40°—40° and 40° force rack 36 upwardly thereby 35 moving link 31 downwardly and raising head 20 through the medium of the intervening gear connections. When cam member 2 revolves to the point where roller 37 moves off of surface 40° and engages groove 38 the rack 40 40 is drawn downwardly and, through the medium of the several connections described, the head 20 is moved downwardly. The movement, however, of head 20 is not uniform throughout its cycle of movement. 45 After the completion of its downward stroke it is drawn slightly upward by cam surface 40° to assist in holding the paper firmly during the perforating process and then is moved by cam surface 40° to a point where 50 its lower surface is flush with the lower end of mold 5 during the time required to fold the end of the paper thereover as hereinafter described. When the folding of the end is completed the cam surface 40° comes into 55 use and raises the head 20 up past the opening 7 from chamber 6.

The paper 43 from which the packages are made is fed in a continuous strip over roller 44 and thence over a pair of formers 60 as 45 and 46 which causes the paper to freely envelop a little over three sides of the mold 5. The paper is brought into close and accurate contact with these three sides of mold 5 by rollers 47 contacting there- 65 with, mounted on pivots 48 on plate 49 sup-

ported on standard 1 by means of rods 50, the said rollers being rendered resilient by springs 51 inserted under projections 52 of brackets 53 in which said rollers are mounted. Upon the fourth side of mold 5 where 70 the two side edges of paper 43 are caused to approach each other, I have mounted a seamer consisting of two parts, one part 54 being on bracket 55 set on plate 49, and the other part 56 on support 57 mounted on 75 mold 5. These two members 54 and 56 have interlocking spaced fingers 58 and 59 respectively whereby the paper edges drawn therethrough are caused to overlap and form a seam, the said seam being completed and 80 rolled flat by roller 60 mounted on plate 49 as shown.

The machine is so constructed that the paper tube is perforated, separated and folded upon the upper end of a filled package at the same time that the bottom of the next package is formed, these operations being performed in the following manner.

Rigidly mounted on the upper surface of standard 1 in the positions shown in Fig. 90 7, are guides 61—62—63—64, each guide having a roller support as 65—66—67—68 slidably mounted therein carrying pairs of rollers as 69—70—71—72 together with perforating knives 73—74—75—76. These 95 slideable members are forced inwardly a short distance to perforate the paper by means of small cams 65a—66a—67a—68a on the inner surface of cam member 2, and withdrawn by spring actuated arms 77—78—79—80 engaging the same and pivoted upon arms as 81—82—83—84 projecting from plate 49. As shown in the present invention the perforating knives 73—75 upon the wide side members 65—67 are straight and positioned 105 to perforate the paper horizontally on each side of the tube as at 85 midway between the rollers on each member. The perforating knives 74—76 on the narrower end members 66—68 are arranged to perforate the narrow 110 sides of the tube as shown in Fig. 12, the perforations at 86 being in line with the side perforations at 85 and the angular perforations 87—88—89—90 being along lines where the paper would naturally be ruptured upon folding in the longer sides. 115

After perforating the paper the sliding members 65—66—67—68 are successively moved forward over the package ends in the following order,—first 65 moves forward 120 and is withdrawn and then 67 moves forward and is withdrawn, these two operations separating the paper along perforations 85—87—88—89 and 90 and folding the several parts as shown in Fig. 13. Next 125 66 moves forward and is withdrawn, its withdrawal being closely followed by the advance and withdrawal of member 68. These last two operations serving to sever the paper along the remaining perforated 130

lines 86 and folding the freed parts over upon the package ends.

When the packages are made of paraffin paper and packed with heated goods, such as prunes fresh from a processor, no additional fastening means for the folded parts is necessary. But when additional fastening means is required the member 67 is formed with a chamber 91 containing glue and suitable wicks as 92 are inserted in the side walls communicating with the chamber and so positioned that when member 67 moves forward a suitable amount of glue will be deposited upon the inner surfaces of the yet unbroken side walls of the tube so that when these walls are folded as shown they will overlap the side walls previously folded and securely seal them all in place. The members 65—66—67—68 are moved forward as above described by suitable cams as 65^b—66^b—67^b—68^b formed on the inner surface of cam member 2 as shown and, of course, in different horizontal planes. They are withdrawn from the rolling operations by the same means that withdraws them from the perforating operations.

The completed package must now be removed ready for placing in a suitable container or carton, and this operation is performed in the following manner.

The completed package is passed downwardly into passage 93 in standard 1, this passage being in alignment with mold 5 and spaced a distance therefrom sufficient to permit the passage of the rollers therebetween. In passage 93 is a vertically operating plunger 94 on rod 95 provided with a pin 96, the latter being slidably engaged by a lever 97 fulcrumed at 98. A link 99 is pivotally connected at one end to lever 97 at 100 and at the other end to a lever 101 pivoted at 102 and pivotally connected to a vertically movable pin 103 at 104, the latter being mounted in bearing 105 in table 3. The upper end of pin 103 supports a roller 106 which operates on a cam surface 107 formed on the under side of cam member 2, this mechanism operating to raise and lower plunger 94 at stated periods hereinafter more fully set forth.

The completed package in passage 93 is removed, when the plunger 94 is in its lowest position, by means of a frame 108 in which it is deposited, the said frame being carried by an arm 109 pivoted at 110 and swinging in a horizontal plane. The mechanism for swinging arm 109 and form 108 consists of a lever 111 pivoted at 112 and slidably connected to a pin 113 on arm 114 formed integrally with arm 109. To the central portion of lever 111 is pivotally attached at 115 a link 116 pivotally connected at its other end 117 to one arm 118 of a bell crank pivoted at 119. The

portion 119 is in the form of a vertically positioned rod as shown and the other arm 120 also has a vertically extending pin 121 at its outer end adapted to engage cams 122—123 formed on the under surface of cam member 2. As cam member 2 revolves cam 123 engages pin 121 and moves it inwardly thereby, through the mechanism described, moving form 108 into standard 1 and in alignment with the passage 93 therein. Since plunger 94 is in a raised position at this time a slot 124 is formed in the form 108 so that the same can pass into the required position without striking rod 95 supporting said plunger 94. A further revolution of cam member 2 causes pin 121 to engage cam 122 thereby forcing the same outwardly and, through the mechanism described, swinging frame 108 outwardly to the position shown in Fig. 11 in which position it is in alignment with the opening 125 in the frame 126 forming a part of table 3.

The wrapped package must now be removed from the machine and placed in a carton. To effect this removal I provide a vertically movable rod 127 passing through the center of the pivoted end of arm 109 and forming a bearing therefor. The upper end of rod 127 is provided with a roller 128 engaging a cam 129 on the lower surface of cam member 2, and the lower end is provided with a laterally extending pin 130. Slidably engaging pin 130 and at one end thereof is a lever 131 pivotally mounted on a bracket 132 and slidably connected at its other end to a pin 133 on vertically movable rod 134 operating in bearing 135 in frame 126 forming a part of table 3. Rod 134 is axially aligned with opening 125 in frame 126 and carries a head 136 substantially as shown. The position of the fulcrum for lever 131 insures the weight of the longer arm thereof maintaining the roller 128 in contact with cam 129 and normally positions plunger 136 in a lowered position as shown in dotted lines in Fig. 2. When however rod 127 is forced down by cam 129 the said plunger head 136 is forced up to a position flush with the top of table 3 so that the package is removed from the machine and inserted in a carton held over opening 125 ready to receive the same by a mechanism not shown. The opening 125 is normally closed by four gates 137—138—139—140 hinged to the side edges as indicated at 137^a—138^a—139^a—140^a. The upward movement of the package automatically opens the gates upwardly so that they will open the folding parts of the carton end and permit the entrance of the package into the carton.

The cam member is revolvably mounted on standard 1 as clearly shown in Fig. 8 130

and is driven by means of a gear 141 formed on the outer perimeter thereof meshing with a pinion 142 operatively mounted in frame 4 and driven by suitable power connections not shown.

In operation cam member 2 is driven in the direction indicated by the arrow in Fig. 2 at a uniform rate of speed, the several different cams preferably being formed 10 integrally therewith.

Assuming a quantity of material to have been deposited in chamber 6, the plunger 8 being in a withdrawn position as shown in Fig. 17. The operation of cam 40 15 through parts 18 to 39 and 40 raises head 20 to a point above opening 7 at the same time through parts 8 to 17 and 19 moving the material in chamber forward where it falls into mold 5, the relative positions of 20 head 20, and plungers 8 and 94 at this time being clearly shown in Fig. 18. Head 20 remains in a raised position during the revolution of cam surface 40^a until the surface 40^b is reached whereupon it is moved 25 downward to compression as shown in Fig. 19 with plunger 94 in the same position as shown in Fig. 18. The downward movement of head 20 is continuous, and after descending a given distance the bottom 30 plunger 94 is also caused to move downwardly a given distance with head 20 and the two packages therebetween as shown in Fig. 20, by means of cam surface 107^a on cam 107 through parts 95—106. Since each 35 new package is formed from a continuous strip of paper the downward movement of the filled package automatically draws down the paper through folding devices 44—48 and 51—60 and forms a new section 40 of paper tube of sufficient length that when cut and folded it will form the ends of two packages.

At this time the newly filled package is held with the top surface of the material 45 therein flush with the surface operated over by the lower rollers 69—70—71—72 and the head 20 is raised a short distance by the cam surface 40^b so that the side walls of the paper tube will be held taut during the perforating operation. With the filled package and plunger 94 and head 20 in the position shown 50 in Fig. 21 the four sliding members 65—66—67—68 simultaneously engage their respective cams 65^a—65^b—65^c—65^d and move forward and cause their respective knives to 55 perforate the paper as hereinbefore described and are immediately withdrawn as described.

Head 20 is now withdrawn by cam surface 40^d to a point as shown in Fig. 22 so that its 60 lower surface is flush with the lower surface of mold 5. This is instantly followed by the forward movement of member 65 actuated by cam 65^a to sever and fold in one side of the paper tube, one-half over the

filled package and one-half over the head 65 20. Upon the withdrawal of member 65, member 67 is moved forward actuated by cams 67^a thereby severing and folding in the opposite side of the tube over the filled package and the head 20. Upon withdrawal 70 of member 67, members 66 and 68 are first one and then the other moved forward and withdrawn thereby completing the folding of the paper over the filled package and forming an end for a new package over 75 head 20 which is then withdrawn by the action of cam surface 40^e to its highest position above opening 7.

The newly completed package is now moved upward to contact with and support 80 the newly formed end of the next succeeding package as shown in Fig. 18 by means of cam surface 107^b on cam 107 and the next cycle of filling, forming and folding a 85 package is begun.

Upon the close of the downward movement of head 20 and plunger 94 the package previously formed and completed is placed in form 108 which has previously been moved into alinement with passage 93 by means of 90 cam 122 and parts 109—121 operated thereby. Immediately upon placing of the package in form 108 cam 123 operates the same parts in an opposite direction to swing the package around to a position in alinement 95 with opening 125 whereupon it is removed as hereinbefore described by the operation of cam 129 and parts 127 to 128 and 130 to 136.

In the cam graphs shown in Figs. 23 to 100 31 inclusive the several graphs are properly positioned with relation to their several periods of operation, the zero line representing the time immediately preceding the perforating operation. By the time the cam 105 member 2 has revolved through 135° the perforating has been done, the folding has been completed, the bottom plunger has just been withdrawn to its lowest point, the top plunger or head 20 has almost reached 110 its highest position, and plunger 8 is just about to move forward to discharge the material in chamber 6 into mold 5.

It is understood of course that I do not 115 wish to confine myself to the specific form of the invention herein set forth but to include all changes in form, construction and method of operation included within the scope of the appended claims.

I claim:

1. A packaging machine including devices for forming a paper tube, means for closing one end of said tube, means for depositing a given quantity of material in said tube, means for compressing said material in said tube, and advancing the same to lengthen said tube, and devices for detaching the filled end of said tube and closing the same 125

to form an individual package simultaneously with the operation of said first mentioned means.

2. A packaging machine including devices for forming a tube of flexible material operable by the movement of said material, means for closing one end of said tube, means for depositing a given quantity of material in said tube, means for advancing the material and said tube thereby operating said tube forming devices to form new tube, and devices for detaching the filled end of said tube and closing the same to form an individual package simultaneously with the operation of said first mentioned means.

3. A packaging machine including devices for forming a tube of flexible material, means for closing one end of said tube, means for depositing a given quantity of material in said tube and advancing the same to lengthen said tube, means for perforating said tube above said filled portion, means for detaching the said filled portion of said tube from the remaining portion thereof along said perforations and means for folding the end of the filled portion of said tube to form an individual package simultaneously with the operation of said first mentioned means.

4. A packaging machine comprising devices for forming a tube of flexible material operable intermittently by the movement of said flexible material, means for intermittently advancing the formed tube to form new tube through the operation of said tube forming devices, means for perforating said tube, and devices for severing one portion of said tube from the other where perforated and simultaneously folding and closing the opposing ends of the severed tube.

5. A packaging machine including devices for forming a tube from a continuous sheet of flexible material, means for interlocking the edges of said material as the tube is formed, means for compressing the interlocking edges, means for advancing the flexible material through said forming devices, means for perforating the sides of the tube along predetermined lines, and means for severing one portion of the tube from the other along said perforated lines and simultaneously folding and closing the opposing ends of the severed tube.

6. A packaging machine including devices for forming a four sided tube of flexible material, means for advancing said material through said forming devices, means for perforating two opposite sides of said tube in a plane perpendicular to the axis of said tube, means for perforating the other two sides in the same plane and also on lines extending inwardly from both ends of said last mentioned perforation and diverging therefrom, and means for severing one portion of the tube from the other along

said perforated lines and folding and closing the opposing ends of the severed tube.

7. A packaging machine including devices for forming a four sided tube of flexible material, means for advancing said material through said forming devices, means for perforating two opposite sides of said tube in a plane perpendicular to the axis of said tube, means for perforating the other two sides in the same plane and also on lines extending inwardly from both ends of said last mentioned perforation and diverging therefrom, means for severing first one and then the other of said first mentioned sides along their respective perforated lines and folding the same over the opposing ends of the severed tube, and means for severing first one and then the other of the said second mentioned sides along their respective perforated lines and folding the same over the opposing ends of the severed tube.

8. A packaging machine including devices for forming a tube of flexible material, means for advancing the formed tube to form new tube, means for perforating said tube, and devices for severing one portion of said tube from the other where perforated and simultaneously folding and closing the opposing ends of the severed tube.

9. A packaging machine including devices for forming a four sided tube of flexible material, means for advancing the formed tube to form new tube, means for perforating the four sides of said tube, means for severing first one and then the other of two sides of one portion of said tube from the other portion and folding the same over the opposing ends of the tube, means for depositing an adhesive substance upon the remaining sides along the perforations therein, and means for severing the remaining sides along said perforations and folding the same over the opposing ends of the tube and the previously folded sides thereon.

10. A packaging machine including devices for forming a tube of flexible material, means for advancing the formed tube to form new tube, means for simultaneously perforating said tube along predetermined lines on all sides thereof, and means for severing one portion of said tube from the other along said perforated lines and simultaneously folding alternate sides of the upper end of the severed tube and the depending end of the unsevered tube.

11. A packaging machine including devices for forming a tube of flexible material, means for depositing a given quantity of material in said formed tube, means for advancing said formed tube and the material therein to form new tube, means for perforating said tube above the filled portion thereof, and devices for severing the filled portion of the tube from the other

portion where perforated and simultaneously folding and closing the upper end of the severed tube and the depending end of the unsevered tube.

- 5 12. A packaging machine including devices for forming a tube of flexible material, means for depositing a given quantity of material in said formed tube, means for advancing said formed tube and comprising the material therein and operating said first mentioned devices for forming new tube, means for perforating said tube above the filled portion thereof, and devices for severing the filled portion of the tube from the other portion where perforated and simultaneously folding and closing the upper end of the severed tube and the depending end of the unsevered tube.

- 10 13. A packaging machine including a mold, devices operatively arranged to form a tube of flexible material about said mold, means for advancing the formed tube beyond said mold and thereby forming new tube, means for perforating said tube, and devices for severing one portion of the tube from the other where perforated and folding and closing the opposing ends of the severed tube.

- 15 14. A packaging machine including a mold, devices operatively arranged to form a tube of flexible material about said mold, means for depositing a given quantity of material in said mold, means for compressing said material therein and advancing the same together with and within said formed tube to form new tube, devices operatively arranged for perforating said tube above the material therein, and devices for severing the filled portion of the tube from the remaining portion where perforated and folding and closing the upper end of the severed tube and the depending end of the unsevered tube.

- 20 15. A packaging machine including a mold and a receiving passage in axial alignment with each other, devices operatively arranged for forming a tube of flexible material about said mold, means for depositing a given quantity of material in said mold, means for compressing said material therein and advancing the same together with and within said formed tube to a position within said receiving passage and forming new tube, means for supporting the walls of the tube above said filled portion in said receiving passage, means for perforating said supported walls, and devices for severing said tube walls where perforated and folding and closing the upper end of the severed tube and the depending end of the unsevered tube.

- 25 16. A packaging machine including devices for forming a tube of flexible material, means for depositing a given quantity of material therein, means for compressing

said material in said tube and advancing the formed tube to form new tube, means for perforating said tube a distance from the filled portion thereof, and means for severing the filled portion of the tube from the remaining portion where perforated and simultaneously folding and closing the upper end of the severed tube and the depending end of the unsevered tube.

70 17. In a packaging machine, means for forming and supporting a tube of flexible material and means for perforating said tube, severing the same along said perforations and folding the severed parts, said means including a movable member provided with perforating means and folding means, means for operating said movable member to perforate said tube, means for withdrawing said movable member after perforating, and means for operating said movable member to sever said tube where perforated and fold the severed parts, and means for withdrawing said movable member after folding the severed parts.

75 18. In a packaging machine, means for forming and supporting a multi-sided tube of flexible material and means for perforating said tube, severing the same along said perforations, and folding the severed parts, said means including a plurality of movable members provided with perforating means and folding means operatively mounted to act simultaneously to perforate said tube and alternately to sever the same along said perforations and fold the severed parts.

80 19. In a packaging machine, means for forming and supporting a tube of flexible material and means for perforating said tube, severing the same along said perforations and folding the severed parts, said means including a slidable member having a perforating knife set therein and roller elements mounted thereon on either side of said knife, means for moving said member forward to perforate said tube with said knife, means for withdrawing said member after perforating said tube, means for moving said member forward to engage the roller elements with said tube, sever the same along said perforations and fold the severed portions over the opposing ends of the severed tube, and means for withdrawing said member to an inoperative position.

21. In a packaging machine, a revoluble cam member, a spaced mold and package receiving passage arranged concentric thereto, devices for forming a tube of flexible material around said mold, material supplying devices actuated by said cam member whereby material is deposited in said tube at predetermined intervals, devices actuated by said cam member for compressing said material in said tube and advancing the same from said mold into said tube thereby operating said tube forming devices to form new tube, devices actuated by said cam member for perforating said tube near the filled portion thereof, and devices actuated by said cam member operatively mounted to sever said tube where perforated and fold the severed portions over the opposing ends of the severed tube.
- 20 22. A packaging machine including devices for forming a tube of flexible material, a cam member revolvably and concentrically mounted with relation to the axis of said tube and having a plurality of cam surfaces thereon, means operable by one cam surface for discharging a given quantity of material into said tube and advancing the same with and within said tube to operate said tube forming devices and form new tube, means operable by a plurality of said cam surfaces for simultaneously perforating the sides of said tube, means operable by a plurality of additional cam surfaces for severing the tube where perforated and folding the same over the opposing ends of the severed tube.
- 25 23. A package forming machine including devices for forming a tube of flexible material, a cam member revolvably and concentrically mounted with relation to the axis of said tube and having an upwardly extending flange formed about the perimeter thereof, the upper edge of said flange being shaped to form a cam, and the inner surface of said flange having a plurality of spaced cams formed thereon in different horizontal planes, and also a plurality of larger spaced cams in different horizontal planes, means operable by first mentioned cam for placing material in said tube and advancing the same to form new tube, means operable by said second mentioned cams for perforating said tube, and means operable by said last mentioned cams for severing said tube where perforated and folding and closing the same over the opposing ends of the severed tube.
- 30 24. A packaging machine including a mold and a receiving passage in axial alignment with each other and spaced a distance apart, devices for forming a tube of flexible material about said mold, means for placing a given quantity of material in said mold and advancing the same with and within said tube into said passage thereby forming new tube, a plunger operatively mounted in said passage to receive said filled tube portion, devices for perforating said tube above said filled portion, devices for severing said tube where perforated and folding and closing the severed portions over the opposing ends of the severed tube to form a filled package and an end for a new package, means for actuating said plunger to raise the package whereby to support the newly formed end of the tube and to withdraw the formed package into said passage upon the advance of the next charge of material in the tube, means for receiving the package withdrawn, means for removing the same from said passage, and means for ejecting said package from said machine.
- 35 25. A packaging machine including a mold and a receiving passage in axial alignment and spaced relation to each other, devices operatively mounted to form a tube of flexible material about said mold, a plunger operatively mounted to reciprocate through said mold to compress material therein and advance the same to said passage in said tube, a plunger operatively mounted to reciprocate in said passage in opposed relation to said first mentioned plunger, devices operatively mounted to perforate, sever and fold the tube over the portion in said passage and over the end of the mold, and means for coördinating the movements of said plungers and perforating and folding devices.
- 40 26. A packaging machine including a mold and a receiving passage in axial alignment and spaced relation to each other, devices operatively mounted to form a tube of flexible material about said mold, a plunger operatively mounted to reciprocate through said mold to compress material therein and advance the same to said passage in said tube, a plunger operatively mounted to reciprocate in said passage in opposed relation to said first mentioned plunger, devices operatively mounted to perforate, sever and fold the tube over the portion in said passage and over the end of said mold, and a cam member provided with a plurality of cams spaced and arranged to coördinate the movements of said plungers and perforating and folding devices.
- 45 27. A packaging machine including a mold and a receiving passage in axial alignment and spaced relation to each other, devices operatively mounted to form a tube of flexible material about said mold, a plunger operatively mounted to reciprocate through said mold to compress material therein and advance the same to said passage in said tube, a plunger operatively mounted to reciprocate in said passage in opposed relation to said first mentioned plunger, devices operatively mounted to perforate, sever and fold the tube over the 100

- portion in said passage to form a complete package and over the end of said mold, devices for discharging the complete package from said machine, and a cam member provided with a plurality of cams spaced and arranged to coördinate the movements of said plungers, perforating and folding devices and devices for discharging the completed package.
10. 28. A package forming machine including devices for forming a tube of flexible material, a cam member revolubly and concentrically mounted with relation to the axis of said tube and having an upwardly extending flange formed about the perimeter thereof, the upper edge of said flange being shaped to form a cam, and the inner surface of said flange having a plurality of spaced cams formed thereon in different horizontal planes, and also a plurality of larger spaced cams in different horizontal planes, means operable by said first mentioned cam for placing material in said tube and advancing the same to form new tube, means operable by said second mentioned cams for perforating said tube, means operable by said third mentioned cams for severing said tube where perforated and folding and closing the same over the opposing ends
- 5 of the severed tube thereby forming a filled package, and a depending flange formed upon the under surface of said cam member, the lower edge of said flange being shaped to form a cam, and means operable by said last mentioned cam surface for raising the filled package to support the closed end of the new tube and to withdraw the filled package simultaneously with the advance of the material in the new tube.
15. 29. The structure set forth in claim 28 in which the cam member is provided with laterally arranged cam surfaces on its under surface, and means operable by said laterally arranged cam surfaces for removing said filled package from the withdrawing means.
20. 30. The structure set forth in claim 28 in which the cam member is provided with laterally arranged cam surfaces on its under surface, means operable by said laterally arranged cam surfaces for removing the filled package from the withdrawing means, and a second depending flange formed upon the under surface of the cam member, the lower edge of said flange being shaped to form a cam, and means operable by said last mentioned cam surface for ejecting the package from said removing means.

ALBERT REYNOLDS.
